FIG. 2. ← 6

FIG. 3.

FIG. 4.

FIG. 5.

FIG. 6.

WITNESS:

Robt. R. Kitchel.

INVENTOR

Rubert Lipsky
BY
Buer and Hardig
ATTORNEY.

UNITED STATES PATENT OFFICE.

RUBIN LIPSKY, OF PHILADELPHIA, PENNSYLVANIA.

COAT.

Application filed February 6, 1924. Serial No. 690,895.

To all whom it may concern:

Be it known that I, RUBIN LIPSKY, a citizen of the United States, residing at Philadelphia, county of Philadelphia, and State 5 of Pennsylvania, have invented a new and useful Improvement in Coats, of which the following is a full, clear, and exact description, reference being had to the accompanying drawings, which form a part of this 10 specification.

My invention relates to coats and more particularly to men's coats. The object of my invention is to so secure the lining to the body as to avoid the provision of any 15 special seam or line of stitches along any exposed part of the body where a seam or line of stitches would not be required in case the lining were omitted, thereby reducing the labor required to make the garment and avoiding the exposure of any special lining stitching thread on the outer 20 face of the body. The invention also provides for a pocket construction of especial utility.

25 In the drawings:

Fig. 1 is a side view, of a part of a coat made in accordance with my invention, looking toward the outside of the coat.

Fig. 2 is a side view of the same part 30 of the coat, looking toward the inside.

Fig. 3 is a section on the line 3—3 of Fig. 1.

Fig. 4 is a section on the line 4—4 of Fig. 2.

35 Fig. 5 is a section on the line 5—5 of Fig. 2.

Fig. 6 is a section on the line 6—6 of Fig. 2.

The drawings show the body portion of 40 the garment by means of a double line connected by cross-hatching, while the lining is represented as a single line; whereby these two parts of the garment are readily distinguishable. In other respects, also, the drawing is somewhat diagrammatic, for purposes of clearness.

The body *a* of the coat has a typical cut or shape, the same having a T-cut represented by the lines *b* and *c*. The cut *c* forms the 45 pocket opening. The cut *b* is for the purpose of shaping the coat, the opposing edges being secured together in the usual manner, forming an inside seam, as indicated at *d*, Fig. 5.

55 Along the front edge of the coat the material of the body is folded in, in the usual

way, as indicated, to form the fold *e*, shown best in Figs. 4 and 5.

The lining *f* is sewed to the upper edge of the body *a* at the shoulder portion and 60 arm-hole, along the inner or concealed edge of the fold *e* of the body, as shown in Figs. 4 and 5, along the seam *d*, as shown in Fig. 5, and to the lower edge of the pocket cut, as shown at *g*, Fig. 3. The lower edge of 65 the lining, and the side edge of the lining below and aligning with seam *d*, are unsecured to the body.

It will be observed that by forming and securing the lining as described, no lines 70 of stitches are required that extend onto the exposed face of the body except the stitches along the line *b*, which line of stitches would be indispensable if the lining were altogether omitted.

75 The lower end portion of the lining is turned in and the fold *h* thus formed is, as above described, secured at its upper edge to the pocket edge formed by the cut *c*, as best shown in Fig. 3. Secured to the flap *i* of the pocket and to the fold *h* of the lining is a strip of material *j* which, together with the fold *h*, forms the pocket pouch. The bottom edge of the lining is made of 80 quadruple thickness by folding in the material and forming the seam *k*, as shown in Figs. 2 and 3.

Having now fully described my invention, what I claim and desire to protect by Letters Patent is:—

1. A coat comprising a body with an in-turned fold along the front edge, the body having a downwardly extending cut for shaping purposes, and a lining secured along one side edge to said in-turned fold of the 90 body, the edges of such cut and a part of the other side edge of the lining being secured together along the same line to form a seam, whereby the lining is secured to the body without providing an extra seam 95 and without extending the stitches onto an unsecured and exposed part of the body.

2. A coat comprising a body with an in-turned fold along the front edge, the body having a downwardly extending cut whose 100 edges are secured together, and a lining secured along one side edge to said in-turned fold of the body and along the upper part of its other side edge to the body along the line of said cut, the bottom edge of the 105 lining and the lower part of the last named side edge being free of the body.

20
3. A coat comprising a body with an in-turned fold along its front edge and having a downwardly extending cut and a pocket opening, a lining, the edges formed by the 5 downwardly extending cut being secured together and the lining being secured to the body along the line of said downwardly extending cut and along said inturned fold, the lower part of the lining being upturned 10 and secured to the edge of the pocket open-

ing, the lining hanging free of the body along its bottom and along the lower part of the side edge thereof below the top of the pocket opening, and a piece of material forming, with the lining, the pocket pouch. 15

In testimony of which invention, I have hereunto set my hand, at Philadelphia, Pa., on this 1st day of February, 1924.

RUBIN LIPSKY.
